DETERGENT COMPOSITION

Wayne L. St. John, Wyoming, Ohio, assignor to The Procter & Gamble Company, Cincinnati, Ohio, a corporation of Ohio

No Drawing. Filed Jan. 20, 1956, Ser. No. 560,280

11 Claims. (Cl. 252—137)

The present invention relates to detergent compositions containing an additive which imparts to these detergent compositions improved sudsing characteristics and more particularly to improvements in the sudsing and suds stability characteristics of detergent compositions containing sulfated and sulfonated anionic detergents.

Synthetic detergents of the anionic sulfated and sulfonated types are known to have excellent deterging properties. Often, however, for purposes of consumer appeal, it is thought to be desirable to increase and improve the sudsing characteristics of these detergent compositions, particularly in regard to products designed primarily to be used for washing dishes, and other kitchen utensils. To the average housewife, the suds floating on a washing solution serves as an indication of the remaining washing power and as a means for covering from sight the solution itself which may take on an unpleasant appearance after being in use a short time. Greasy materials and scraps of food are often carried into the washing solution. The addition of an alkali metal tripolyphosphate to the anionic sulfated and sulfonated detergents is known to improve the sudsing characteristics of these detergents as well as to impart to the compositions thus formed other improvements, in respect to economy, detergency, and mildness. However, even with these improved compositions, as well as with anionic sulfated and sulfonated detergent compositions which do not contain tripolyphosphate there may be a tendency to wastefully add to a dishwashing solution the detergent composition in an amount, based on the quantity of suds formed, greater than that necessary to achieve adequate detergency.

It is an object of the present invention to provide detergent compositions which display improved sudsing characteristics.

It is a further object to provide, as additives for detergent compositions containing sulfated and sulfonated anionic detergents, a class of compounds having an exceptional ability to increase and improve these detergent compositions in respect to sudsing and suds stability characteristics.

It is another object to provide a means for overcoming the disadvantages referred to in connection with the washing of dishes, kitchen utensils, etc.

Further objects and advantageous features will appear from the following detailed description.

In general, the present invention relates to the recognition of the alkylurea glycosides as a class of compounds which when present in minor amounts, impart to the active detergent in a detergent composition greatly improved sudsing and suds stability characteristics, especially when these compositions are used at customary dishwashing and laundering temperatures.

The following structural formulas will serve to indicate the range of compounds included within the scope of my invention:

and

2

wherein R is a higher alkyl radical having from about ten to about fifteen carbon atoms and R' is either a mono-saccharide or a reducing oligosaccharide. The structural formulas indicated that I include compounds in which the carbohydrate moiety is attached to either of the nitrogen atoms of the urea moiety. Either or both of the hydrogen atoms can be substituted by low molecular weight alkyl or alkylol groups such as methyl, ethyl, propyl, methylo, ethanol, propanol and dihydroxy propyl.

5 The lower alkyl and the lower alkylol groups should not contain in excess of three carbon atoms each, and the lower alkylol groups may be mono- or polyhydroxy in structure. The polyalkyl and polyalkylol derivatives of the alkylurea glycosides may be symmetrical or unsymmetrical.

10

15

20

Specific examples and structural formulae of compounds which come within the scope of the above general formula and which may be employed in the practice of the present invention are:

(1) Dodecylurea-N'-glucoside

(2) Dodecylurea-N-glucoside

(3) Pentadecylurea-N'-galactoside

(4) N-decyl-N'-methylurea-N'-glucoside

(5) N-dodecyl-N-ethyl-N'-methylurea-N'-glucoside

(6) N-dodecyl-N,N'-dimethylurea-N'-lactoside

(7) N-dodecyl-N'-ethanolurea-N'-glucoside

(8) N-decyl-N,N'-diethanolurea-N'-riboside

It will be understood that when either a specific alkylurea glycoside or the alkylurea glycosides as a class is referred to, both the alpha and beta substituted ring forms are intended to be encompassed. The alpha and beta forms of the alkylurea glycosides may be exemplified by the following structural formulae of alpha and beta dodecylurea-N'-glycoside:

Methods for the preparation of the alkyl ureas, alkylalkylol ureas, mixed polyalkyl ureas, etc. are numerous and are well known in the art. Several means of preparing alkylurea glycosides are known in the art; one method may be illustrated by the preparation of dodecylurea-N'-glucoside: A mixture of 22.8 g. of dodecylurea, 19.8 g. of glucose, 2.5 g. of concentrated hydrochloric acid and 200 ml. of 95% ethyl alcohol is stirred and heated at 50° C. for 100 hours, then cooled and filtered. The product is washed successively with water and hot benzene.

All monosaccharides and reducing oligosaccharides can condense with the alkylureas to form alkylurea glycosides. In order for the condensation to proceed it is necessary that there be present a monosaccharide or an oligosaccharide having a monosaccharide residue with unsubstituted hemiacetal hydroxyls. When such unsubstituted hemiacetal hydroxyls are present, the oligosaccharides reduce alkaline copper-salt solutions, mutarotate, and form glycosides as do the monosaccharides. In the absence of a reducing group, none of these reactions are exhibited.

The term oligosaccharides is used to differentiate the di-, tri- and tetrasaccharides from the monosaccharides. The following oligosaccharides, since they do not contain unsubstituted hemiacetal hydroxyls, will not condense with the alkylureas to give the desired alkylurea glycosides: sucrose, trehalose, melititose, raffinose, gentianose, labiose, and stachyose. Examples of oligosaccharides which, because of the presence of unsubstituted hemiacetal hydroxyls, are reducing carbohydrates, and which will condense with the alkylureas to form alkylurea glycosides are as follows: maltose, lactose, cellobiose, melibiose, etc.

Water soluble salts of sulfonic acids which exhibit detergent effect, such as the higher alkylated benzene sulfonic acids (e.g. potassium salt of the sulfonic acid de-

rived from the condensation product of benzene and a chlorinated kerosene fraction containing predominantly twelve carbon atoms per molecule, or the sodium salt of the sulfonic acid derived from the condensation product of benzene and polypropylenes having from 9 to 15 carbon atoms and averaging 12 carbon atoms) are greatly improved in respect to their sudsing properties by addition thereto of a smaller amount of the substituted amides mentioned above. Also, water soluble salts of higher mono fatty acid esters of 1,2-dihydroxypropane-3-sulfonic acid (sodium salt of the coconut oil fatty acid monoester of this sulfonic acid is a specific example) will find use in the practice of this invention. In addition, water soluble salts of higher fatty acid monoesters of lower molecular weight hydroxy alkyl sulfonic acids (e.g. oleic acid ester of the sodium salt of isethionic acid) and of the higher fatty acid amides of lower molecular amino alkyl sulfonic acids (e.g. ammonium salt of oleic acid amide of N-methyltaurine) can be employed. Likewise detergent compositions which display improved sudsing characteristics in the practice of my invention can be prepared from synthetic detergents such as the water soluble salts of the higher alcohol esters of sulfocarboxylic acids (e.g. sodium salt of the lauryl alcohol ester of sulfoacetic acid) and ethers of high molecular alcohols and lower hydroxy sulfonic acids (e.g. monolauryl ether of 1,2-dihydroxy propane-3-sodium sulfonate).

Other synthetic detergents which are useful in the practice of my invention include the water soluble salts of high molecular aliphatic sulfuric acid esters such as the alkali metal, ammonium and substituted ammonium salts of sulfuric acid esters of normal primary aliphatic alcohols having twelve to eighteen carbon atoms, particularly those whose principal active ingredient is a water-soluble salt of lauryl sulfuric acid or oleyl sulfuric acid. Specific examples are the sodium alkyl sulfate obtained from the mixed higher alcohols produced by the reduction of coconut oil, palm kernel oil, or other oils of the coconut oil group (a group of tropical nut oils characterized by their high content of combined fatty acids having 10 to 15 carbon atoms), tallow or sperm oil. Also, water soluble salts of sulfuric acid esters of higher fatty acid monoglycerides (e.g. sodium salt of the coconut oil fatty acid monoester of 1,2-dihydroxy propane-3-sulfuric acid ester) and of the sulfated higher fatty acid alkylolamides (e.g. sodium salt of sulfated coconut oil fatty acid ethanolamide) may be employed. Included among these synthetic detergents are the water soluble salts of higher alkyl polyethylene oxide sulfuric acid esters (e.g. the sulfated and neutralized reaction product of about three moles of ethylene oxide with one mole of the higher alcohols produced by the reduction of coconut oil fatty acids having 10-14 carbon atoms).

Any of the above detergents may be used either alone or in admixture.

The above examples are merely specific illustrations of the numerous detergents which, with or without the addition of an alkali metal tripolyphosphate, can be rendered more efficient in their sudsing characteristics when used in conjunction with the alkylurea glycosides in accordance with my invention, and I do not wish to be limited thereto. The concentration of these detergents in the cleansing and laundering compositions of the present invention is generally from about 12% to about 50% by weight of total product and preferably from about 12% to about 30% by weight of total product.

These detergents may be used singly or in combination with auxiliary materials, which may include any of the substances customarily employed by the art, in admixture with sulfated and/or sulfonated organic synthetic detergents. The various alkali metal phosphates (e.g. tripolyphosphate and higher polyphosphates, hexametaphosphate, pyrophosphate, and orthophosphate), the alkali metal silicates, sulfates, carbonates, etc. are illustrative but not exhaustive examples of these auxiliary materials.

When it is considered desirable to incorporate an alkali metal tripolyphosphate into the detergent compositions of the present invention, the optimum ratio of the tripolyphosphate to active synthetic detergent is from about 2.5:1 to about 3:1. However, improved sudsing performance, attributable to the above designated suds building additives, can be demonstrated when the ratio of the tripolyphosphate to active synthetic is from about 1:1 to about 5:1.

The alkylureas, which have been heretofore suggested for use in detergent compositions as suds-builders and detergency additives (Ross, 2,708,183) are characterized by their limited water solubility. The substitution of a monosaccharide or a reducing oligosaccharide for an amino hydrogen on the urea moiety of an alkyl urea results in a distinctly different class of compounds, the members of which have considerably greater water-solubility than the alkylureas and which are greatly superior to the alkylureas in respect to suds-building performance. These alkylurea glycosides contain in their molecular structure both hydrophobic (higher alkyl) and hydrophilic (carbohydrate) groupings.

Dodecylurea-N'-glucoside may be considered to be representative of the alkylurea glycosides which form a part of the present invention. Dodecylurea may likewise be considered to be representative of the alkylureas. Dodecylurea-N'-glucoside has been found to be greatly superior to dodecylurea as a suds builder. In the following tabulation the monoethanol amide of coconut oil fatty acids, hereafter designated as coconut ethanolamide, has been selected as a standard for comparison since it is one of the most widely known and commonly used organic suds builders. The percentages in the following table are relative to coconut ethanolamide at 100%. All three detergent compositions contain 17.5% alkyl benzene sulfonate, 32.5% sodium sulfate, 47% sodium tripolyphosphate, and 3% of the specified organic suds-builder.

TABLE I

	Dishwashing Test	Laundry Test
	Percent Suds relative to coconut ethanolamide at 115° F.	Average Suds First two loads; Percent relative to coconut ethanolamide
Coconut ethanolamide.....	(100)	(100)
Dodecylurea-N'-glucoside.....	115	124
Dodecylurea.....	60	109

In the dishwashing test, dishes were washed by hand in a dishpan containing 115° F. water to which a standardized amount of a detergent composition was added. As increasing numbers of plates soiled with equal amounts of a standardized simulated soil are washed, the height of the suds over the solution decreases. The results of the dishwashing test are expressed in terms of comparative average suds endurance in the presence of soil, based on decrease in suds height, in tests run on these soiled plates. The results expressed in the column headed "Laundry Test" were obtained by washing standardized swatches soiled with a standardized synthetic soil in a laundry test using 140° F. water. In both the dishwashing and laundry tests the water contained 7 grains of hardness per gallon.

When either the dishwashing test or the laundry test is used as a criterion for suds building performance, dodecylurea-N'-glucoside is markedly superior to dodecylurea or coconut ethanolamide, according to the results tabulated in Table I.

In the improved detergent compositions of the present invention, the amount by weight of the alkylurea glycoside suds building additives employed is sufficient to increase the sudsing performance of the detergent composition and is at least 1/2% of the total product, but usually is not

greater than the amount by weight of active detergent present. Thus, it has been found that the proportion of active detergent to alkylurea glycoside in the compositions of the present invention will be within the range of about 100:1 to about 1:1. For example, in those improved detergent compositions which contain from about 12% to about 50% by weight of active detergent, based on the total product, from about 1/2% to about 12% by weight, based on total product, of the alkylurea glycoside or the lower alkyl and/or alkylol nitrogen substituted alkylurea glycosides will preferably be used. Particularly effective high suds building performance is achieved when such alkylurea glycosides constitute from about 1% to about 6% by weight of the total product in such detergent compositions.

The following samples are additionally illustrative of the nature of the present invention, and it will be understood that the invention is not limited thereto. Parts shown are by weight.

Example I

To 50 parts of commercial sodium alkyl benzene sulfonate (the sodium salt of the sulfonic acid of the condensation product of benzene and a mixture of polypropylenes having from 9 to 15 carbon atoms and average 12 carbon atoms) containing 35% active constituent are added 47 parts of sodium tripolyphosphate and 3 parts of dodecylurea-N'-glucoside. A slurry of the above composition shows outstandingly improved sudsing performance in both dishwashing and laundry tests over that displayed by compositions in which the dodecylurea-N'-glucoside is replaced with dodecylurea or coconut ethanol amide at the same concentration.

Example II

35 A detergent composition similar to that set forth in Example I with, however, sodium myristyl sulfate substituted in whole or in part for alkyl benzene sulfonate displays a similar improved sudsing performance.

Example III

40 Another detergent composition which shows improved sudsing performance is prepared by compounding 17% of the monoglyceride sulfate of the higher alcohols derived from coconut oil, 31% sodium sulfate, 40% sodium tripolyphosphate, and 12% tetradecylurea-N'-glucoside. Other detergent compositions which possess surprisingly improved sudsing characteristics are as follows.

Example IV

50 17.5% of alkyl benzene sulfonate of polypropylenes having from 9 to 15 carbon atoms and averaging 12 carbon atoms, 32.5% sodium sulfate, 47% sodium tripolyphosphate, and 3% dodecylurea-N'-galactoside.

Example V

55 15% of the sodium salt of the monosulfuric acid ester of the higher alcohols derived from coconut oil and having predominantly 10 to 14 carbon atoms, 22% sodium sulfate, 62% sodium tripolyphosphate and 1% dodecylurea-N'-lactoside.

Example VI

60 40% of alkyl benzene sulfonate of polypropylenes having from 9 to 15 carbon atoms and averaging 12 carbon atoms, 57% sodium sulfate and 3% dodecylurea-N'-glucoside.

The present invention is not to be limited to any particular procedure for mixing the alkylurea-N'-glycosides and the sulfate and sulfonate detergents with or without the addition of alkali metal tripolyphosphates. These components may be incorporated in the detergent composition in any of the forms in which such compositions are manufactured. The glycosides may be mechanically mixed in; they may be crushed into the detergent composition in the form of a slurry, and they may be dis-

solved in a solution of the detergent composition. While such ready-for-use mixtures may be manufactured and may be preferable for many purposes, it is likewise within the scope of the present invention to add the glycosides to water prior to the adding of the detergent alone or detergent and alkali metal tripolyphosphate or vice versa, or to add detergent and alkylurea-N'-glycoside, or detergent, alkylurea-N'-glycoside and alkali metal tripolyphosphate simultaneously but separately to the water.

While the present invention has been described with reference to specific examples and formulations, I do not wish to be limited thereto. Modifications and variations of these specific examples and formulations will be readily apparent to those skilled in the art and it is not intended that the specific examples and formulations contained herein should limit the scope of the invention.

Having thus described my invention, what is claimed

1. A cleansing and laundering composition having improved sudsing power at dishwashing temperatures, consisting essentially of at least one synthetic organic detergent component selected from the group consisting of the water-soluble anionic sulfate and sulfonate detergents as the essential cleansing agent and as a suds-promoting agent an alkylurea glycoside selected from the group consisting of

and

wherein R is a higher alkyl radical of about 10 to about 15 carbon atoms and R' is a carbohydrate selected from the group consisting of monosaccharides and reducing disaccharides, the amount by weight of said alkylurea glycoside being not greater than the amount of the detergent but sufficient to increase the sudsing performance thereof.

2. The cleansing and laundering composition of claim 1 containing an alkali metal tripolyphosphate in an amount by weight of from about one to about five times the amount by weight of active detergent.

3. A cleansing and laundering composition having improved sudsing power at dishwashing temperatures consisting essentially of at least one synthetic organic detergent component selected from the group consisting of the water-soluble anionic sulfate and sulfonate detergents as the essential cleansing agent and as a suds-promoting agent about 1/2 to about 12% by weight, based on total product, of alkylurea glycoside selected from the group consisting of

and

wherein R is a higher alkyl radical of about 10 to about 15 carbon atoms and R' is a carbohydrate selected from the group consisting of monosaccharides and reducing disaccharides, the amount by weight of said alkylurea glycoside being not greater than the amount of the detergent but sufficient to increase the sudsing performance thereof.

4. The cleansing and laundering composition of claim 3 containing an alkali metal tripolyphosphate in an amount by weight of from about one to about five times the amount by weight of active detergent.

5. A cleansing and laundering composition having improved sudsing power at dishwashing temperatures consisting essentially of at least one synthetic organic detergent component selected from the group consisting of the water-soluble anionic sulfate and sulfonate detergents as

the essential cleansing agent and as a suds-promoting agent an alkylurea glycoside selected from the group consisting of

and

wherein R is a higher alkyl radical of about 10 to about 15 carbon atoms and R' is a carbohydrate selected from the group consisting of monosaccharides and reducing disaccharides, the ratio by weight of said detergent to said alkylurea glycoside being from about 100:1 to about 1:1 and being sufficient to increase the sudsing performance of said cleansing and laundering composition.

6. The cleansing and laundering composition of claim 5 containing an alkali metal tripolyphosphate in an amount by weight of from about one to about five times the amount by weight of active detergent.

7. A cleansing and laundering composition having improved sudsing power at dishwashing temperatures consisting essentially of a synthetic organic detergent component selected from the group consisting of the water-soluble anionic sulfate and sulfonate detergents as the essential cleansing agent and as a suds-promoting agent an alkylurea glycoside selected from the group consisting of from about 1% to about 6% by weight, based on total product, of dodecylurea glycoside in an amount sufficient to increase the sudsing properties of said cleansing and laundering composition.

8. The cleansing and laundering composition of claim 7 containing an alkali metal tripolyphosphate in an amount by weight of from about one to about five times the amount by weight of active detergent.

9. A cleansing and laundering composition having improved sudsing power at dishwashing temperatures consisting essentially of a synthetic organic detergent component selected from the group consisting of the water-soluble anionic sulfate and sulfonate detergents as the essential cleansing agent and as a suds-promoting agent about 1/2% to about 12% by weight based on total product, of a lower alkyl and lower alkylol nitrogen-substituted alkylurea glycoside selected from the group consisting of:

and

wherein R is a higher alkyl radical of about 10 to about 15 carbon atoms, R' is a carbohydrate selected from the group consisting of monosaccharides and reducing disaccharides, the amount of said lower alkyl and lower alkylol nitrogen-substituted alkylurea glycoside being sufficient to increase the sudsing performance of said cleansing and laundering composition.

10. A cleansing and laundering composition having improved sudsing power at dishwashing temperatures consisting essentially of a synthetic organic detergent component selected from the group consisting of the water-soluble anionic sulfate and sulfonate detergents as the essential cleansing agent and as a suds-promoting agent about 1% to about 6% of an alkylurea glycoside selected from the group consisting of:

and

wherein R is a higher alkyl radical and R' is a carbohydrate selected from the group consisting of monosaccharides and reducing disaccharides, the amount of said alkylurea glycoside being sufficient to increase the sudsing performance of said cleansing and laundering composition.

11. A cleansing and laundering composition having improved sudsing power at dishwashing temperatures consisting essentially of a water-soluble alkyl benzene sulfonate as the essential cleansing agent and as a suds-promoting agent about 1% to 6% by weight, based on total product, of an alkylurea glycoside selected from the group consisting of:

15

and

5 wherein R is a higher alkyl radical of about 10 to 15 carbon atoms and R' is a carbohydrate selected from the group consisting of monosaccharides and reducing disaccharides.
